UNITED STATES PATENT OFFICE.

ARTHUR LEE LIGON, OF LOBO, TEXAS.

SINGLE WELL CYLINDER.

1,120,826.

Specification of Letters Patent. Patented Dec. 15, 1914.

Application filed December 2, 1913. Serial No. 804,227.

To all whom it may concern:

Be it known that I, ARTHUR LEE LIGON, a citizen of the United States of America, residing at Lobo, in the county of El Paso 5 and State of Texas, have invented certain new and useful Improvements in Single Well Cylinders, of which the following is a specification, reference being had therein to the accompanying drawing.

10 This invention relates to an improved single well cylinder pump, and the principal object of the invention is to provide an improved pump which is so constructed that it may be very efficiently operated in a deep 15 well, and which is so constructed that the cylinder may be readily removed when desired.

Another object of the invention is to provide the piston with an improved head so 20 constructed that the oil may be forced past the head on the down stroke and then carried up the well tube upon the return stroke.

Another object of the invention is to provide the inner cylinder with a choke plug at 25 its lower end provided with a valve so that when the plug is in place the oil which is sucked into the cylinder past the valve of the plug will be prevented from flowing back into the well.

30 With the above and other objects in view this invention consists of certain novel combinations, constructions and arrangements of parts as will be hereinafter fully described and claimed.

35 In the accompanying drawing:—Figure 1 is a sectional view through the pump. Fig. 2 is a sectional view through the outer cylinder of the pump. Fig. 3 is a section taken along the line 3—3, of Fig. 1. Fig. 4 is a 40 section taken along the line 4—4, of Fig. 1. Fig. 5 is a section taken along the line 5—5, of Fig. 1.

In the accompanying drawings the numeral 10 indicates the lower end portion of 45 the well tube. This tube 10 is connected with the outer cylinder 11 of the pump by means of a coupling 12 which is threaded upon the tube and outer cylinder and is provided with internal teeth 13 so that the inner cylinder can be removably connected 50 with the outer cylinder. A tapered collar 14 connects the outer cylinder 11 with the lower pipe 15 of the well tube. This collar 14 is tapered so that a valve seat 16 is provided. This valve seat forms a rest for the

plug 17 which is in threaded engagement with the lower ends of the threaded cylinder 18. The plug 17 is provided with washers 19 which engage the seat 16 and form a tight joint so that the oil in the space between the two cylinders 11 and 18 cannot flow back into the well. This plug is provided with a central opening 20 which communicates with the interior of the cylinder 18 so that oil can be sucked up into the cylinder 18 when the piston is making its up stroke. A valve 21 has its stem 22 slidably connected with the yoke 23 and is held in the position shown in Fig. 1 so that it may be raised upwardly to permit the oil to flow 60 into the cylinder 18 and then drop back upon its seat, thus preventing the oil from flowing back into the pipe 15. A head 24 is threaded into the upper end portion of the inner cylinder 18 and is provided with 65 pivot ears 25 with which the pawls 26 are pivotally connected. These pawls are engaged by the springs 27 and are normally held in such a position so that their upper ends will engage the teeth 13 and the inner cylinder thus prevented from moving upwardly when the piston moves upwardly. The pump rod 28 extends into the inner cylinder 18 and carries a piston head 29 which is held in place by the collar 30 and jam 70 nuts 31. This piston head is provided with the usual cups 32 so that a suction is formed as the piston is moved, thus causing the oil to be sucked into the inner cylinder 18. A valve disk 33 is mounted above the piston head as shown in Fig. 1 and is intended to 75 close the openings 34 when the piston is moving upwardly. There is sufficient space between the upper face of the valve 33 and the flange of the collar 3 so that when the piston moves downwardly the disk 33 can 80 move away from the piston head and permit the oil to flow through the piston head. A tapered sleeve 35 is mounted upon the piston rod above the collar 30 so that when the 85 pump rod is drawn upwardly a certain amount the sleeve 35 will engage the lower ends of the pawls 26 and move these pawls against the tension of the springs 27. This will release the inner cylinder and permit 90 the inner cylinder to be withdrawn from the outer cylinder when the pump rod is 95 withdrawn from the well.

The operation of this device is as follows:—The inner cylinder is lowered into 100

the well together with the pump rod and when it reaches the outer cylinder 11 the plug 20 will rest upon the valve seat 16 and the pawls 26 will engage the teeth 13, thus securely holding the inner cylinder in place. As the pump rod is moved upwardly oil will be sucked into the inner cylinder past the valve 21 until the piston head has reached its highest point of travel. The 10 pump rod will then move downwardly and since the valve 21 will close, the oil will be forced through the openings 34 past the valve 30 and into the upper portion of the inner cylinder. Upon the second upward 15 stroke the oil in the upper portion of the cylinder will be forced into the tube 10 as more oil is sucked into the lower portion of the cylinder 18 and will finally be forced out of the upper end of the tube 10 as the 20 pumping is continued.

Having thus described the invention what is claimed as new, is:—

1. A pump comprising a tube, an outer cylinder, a collar connecting said tube and outer 25 cylinder and provided with internal teeth, a collar at the lower end of said cylinder forming a valve seat, an inner cylinder positioned within said outer cylinder, a head carried by said inner cylinder, pawls pivotally connected with said head and normally engaging the teeth of said first mentioned collar, a hollow plug at the lower end of said inner cylinder resting upon the valve seat of said lower collar, an inwardly 30 opening valve controlling the passage of fluid through the hollow plug into said inner cylinder, a pump rod extending through said head into said inner cylinder, a piston head at the inner end of said pump rod provided with openings permitting fluid in said inner cylinder to pass into said piston head into the upper portion of the inner cylinder, an upwardly opening valve 35 normally closing the openings formed in said piston head, and a tapered collar carried by said pump rod above said last mentioned valve and adapted to engage said pawls whereby said pawls may be swung out of engagement with the teeth of said 40 first mentioned collar when said pump rod 45

is drawn upwardly to withdraw said inner cylinder from said outer cylinder.

2. A pump including an outer cylinder, a collar at the upper end of said outer cylinder provided with internal teeth, a collar at the lower end of said outer cylinder forming a valve seat, an inner cylinder, a head carried by said inner cylinder, spring 55 pressed pawls pivotally connected with said head and engaging said teeth to hold said inner cylinder in a normal position, a hollow plug at the lower end of said inner cylinder resting upon the valve seat of said lower collar, an inwardly opening valve normally closing the opening formed in said plug, a pump rod 60 extending into said inner cylinder, a hollow piston carried by said pump rod, an upwardly opening valve controlling the passage of liquid through said piston, and means carried by said pump rod for engaging said pawls to throw the same out of engagement with the teeth of said upper collar.

3. A pump including an outer cylinder, a collar carried by said outer cylinder and provided with internal teeth, a lower collar carried by said outer cylinder and provided with an internal valve seat, an inner cylinder, a hollow valve control plug at the lower end of said inner cylinder resting 75 upon the valve seat of said lower collar, a hollow head at the upper end of said inner cylinder, pawls carried by said head and engaging the teeth of said upper collar, a pump rod extending into said cylinder, a 80 valve control hollow piston head carried by said pump rod within said inner cylinder whereby fluid may be sucked into said cylinder past the valve of said plug and forced through said hollow piston head into the 85 upper portion of said inner cylinder, and means carried by said pump rod for engaging said pawls to lock the same out of engagement with said teeth.

In testimony whereof I hereunto affix my 95 signature in presence of two witnesses.

ARTHUR LEE LIGON.
